UNITED STATES PATENT OFFICE

KARL GRÜNWALD, OF BERLIN-WILMERSDORF, GERMANY

TOBACCO MOISTENING DEVICE

Application filed July 6, 1928, Serial No. 290,774, and in Germany May 4, 1928.

Tobacco moistening devices are known, in which a layer capable of retaining moisture is wrapped up in a material which is impervious to moisture. The known constructional forms have the disadvantage that the water of the moisture retaining layer easily comes in contact with the tobacco or the cigarettes, so that the cigarettes become damaged.

According to the present invention the layer which is impervious to moisture projects so far beyond the moisture retaining layer at all those edges or cross-sectional areas, at which it can give off moisture, that the moisture given off cannot be transmitted directly to the tobacco but only to the air of the container in which the tobacco is stored. In order that a considerable amount of moisture shall be given off, perforations may be provided in the tobacco moistening device, the edges of the material which is impervious to moisture being slightly turned up so as to cover the moisture retaining layer to a certain degree. A metal foil may suitably be used as the material which is impervious to moisture. In place of metal foils, materials sprayed with metal or any other non-porous flexible substances may be used as the impervious material.

Various constructional examples of the present invention are shown in the accompanying drawings, in which,

Fig. 1 represents an insertion, in which the moisture is given off only at the edges of the moisture retaining layer,

Fig. 2 a section on line II—II of Fig. 1,

Fig. 3 a view of an insertion which is perforated on one side and opened at one edge,

Fig. 4 a section on line IV—IV of Fig. 3,

Fig. 5 an insertion perforated on both sides,

Fig. 6 a section on line VI—VI of Fig. 5,

Fig. 7 a section through another constructional form.

The insertion consists of a moisture retaining layer 1 of moistened blotting or absorbent paper and a sheath 2 of metal foil or the like which is impervious to water. The layer 1 is wrapped up in the sheath 2 so that the insertion is in contact with the

outer air either only at the lateral edges, as shown in Figs. 1 and 2, or additionally as regards the superficial areas of the perforations 3, which may be of any shape, as shown in Figs. 3—7. The given off moisture must not directly reach the contents of the container into which the insertion is placed after the blotting paper has been moistened, but may only be imparted to the air in the container, for instance cigarette box. For this purpose the sheath 2 has an edge 4 projecting beyond the sheet of blotting paper. When the insertion is laid on the top of the cigarettes contained in the box, only that side which is the lower one when it is being inserted need so project, as is assumed in Figs. 1—6. If, however, the insertion is to be laid between different layers of cigarettes, the upper covering sheet 2 must also be widened so that in this case as well an edge 5 will be produced (Fig. 7).

According to Figs. 1 and 2 moisture is only given off through the lateral edges of the blotting paper, therefore relatively slowly. When it is desired that the water shall be imparted more rapidly to the air the covering layer and the blotting paper is perforated, either as shown in Figs. 3 and 4, only the lower covering layer and the blotting paper being perforated, or so that the holes extend right through as in Figs. 5—7. In both cases provision must be made that no moisture can reach the cigarettes at the perforated areas. For effecting this, when the perforations are being made, the material of the covering layer is bent up to form a rim 7 which partially covers the edges of the perforations in the blotting paper and thus prevents drops of liquid trickling out directly on to the cigarettes. When the perforations are made by stamping, these edges will as a rule be bent up in any case. It is then only necessary to provide that the perforations are stamped out from the side on which is the broader covering layer, the edges of which project beyond the blotting paper, and the insertions must of course be placed in a corresponding manner into the cigarette box.

If the insertion is to be placed between the cigarettes, it is necessary after the holes have been punched to bend in the edges of the perforations on the upper covering plate 5 in a separate operation, so that turned in edges 8 are produced (see Fig. 7).

In the constructional examples shown, only the two longitudinal edges of the sheet of blotting paper are exposed for giving off 10 moisture to the air, the two transverse edges being covered by the metal foil being bent over. If the blotting paper be fixed in the insertion in a different manner, the other edges might also remain open. Thus, for 15 instance, in order that all the edges of the moisture retaining layer shall be open, metal foils might be stuck on the blotting paper by means of a waterproofing adhesive, in which case a further insulating layer formed 20 by the adhesive would be produced, which would prevent the metal corroding. In this case it would of course also be necessary for the covering layer to project beyond the sheet of blotting paper at the side of the 25 insertion which is to rest against the cigarettes or at both sides.

The invention is more particularly intended for insertion in cigarette boxes, but may of course, be used when storing other tobacco manufactures. It may also be used 30 for insertion in cigarette cases in which case it is only necessary to provide suitable devices, for instance spring clamps, for holding the insertion firmly in the cover of the case.

35 The insertion is always placed in the box or case in question, after the sheet of blotting paper has been moistened.

What I claim is:

40 1. In a self-contained tobacco-moistener adapted for use as an integral unit, the combination with an apertured moisture-retaining layer, of a sheath of moisture-impervious material adapted to embrace both surfaces of said layer with exposure of opposite edges 45 of the same and to project beyond the exposed edges of said layer on at least one side thereof, the said sheath having apertures adjacent to at least one surface of the embraced layer, which correspond to, and are 50 slightly smaller than, the apertures in the said layer, so that an overlap is formed around the contour of each aperture in the embraced layer, said overlap being bent over the edge surfaces of the perforations in the 55 embraced layer so as partially to cover them.

2. In a self-contained tobacco-moistener adapted for use as an integral unit, the combination with an apertured moisture-retaining layer, of a sheath of moisture-impervious 60 material adapted to embrace both surfaces of said layer with exposure of a pair of opposite edges of the same and to project beyond the exposed edges of said layer on at least one side thereof, the said sheath having apertures adjacent to at least one surface of the 65

embraced layer, which correspond to, and are slightly smaller than, the apertures in the said layer, so that an overlap is formed around the contour of each aperture in the embraced layer, said overlap being bent over the edge surfaces of the perforations in the 70 embraced layer so as partially to cover them.

3. In a self-contained tobacco-moistener adapted for use as an integral unit, the combination with an apertured moisture-retaining 75 layer, of a sheath of flexible moisture-impervious material adapted to embrace both surfaces of said layer with exposure of opposite edges of the same and to project beyond the exposed edges of said layer on at 80 least one side thereof, the said sheath having apertures adjacent to at least one surface of the embraced layer, which correspond to, and are slightly smaller than, the apertures in the 85 said layer, so that an overlap is formed around the contour of each aperture in the embraced layer, said overlap being bent over the edge surfaces of the perforations in the embraced layer so as partially to cover them.

4. In a self-contained tobacco-moistener adapted for use as an integral unit, the combination with an apertured moisture-retaining layer, of a sheath of flexible moisture-impervious material adapted to embrace both 90 surfaces of said layer with exposure of a 95 pair of opposite edges of the same and to project beyond the exposed edges of said layer on at least one side thereof, the said sheath having apertures adjacent to at least one surface of the embraced layer, which correspond to, and are slightly smaller than, the apertures in the 100 said layer, so that an overlap is formed around the contour of each aperture in the embraced layer, said overlap being bent over the edge surfaces of the 105 perforations in the embraced layer so as partially to cover them.

5. In a self-contained tobacco-moistener adapted for use as an integral unit, the combination with an apertured moisture-retaining layer, of a thin metallic sheath adapted 110 to embrace both surfaces of said layer with exposure of opposite edges of the same and to project beyond the exposed edges of said layer on at least one side thereof, the said 115 sheath having apertures adjacent to at least one surface of the embraced layer, which correspond to, and are slightly smaller than, the apertures in the said layer, so that an overlap is formed around the contour of each aperture in the embraced layer, said overlap being bent over the edge surfaces of the 120 perforation in the embraced layer so as partially to cover them.

6. In a self-contained tobacco-moistener 125 adapted for use as an integral unit, the combination with an apertured moisture-retaining layer of moisture-impervious material secured to the sides of said layer so as to leave opposite edges of the latter exposed and 130

adapted to project beyond the exposed edges of said layer on at least one side thereof, the said moisture-impervious material having apertures adjacent to at least one surface of the moisture-retaining layer which correspond to, and are slightly smaller than, the apertures in the said layer, so that an overlap is formed around the contour of each aperture in the moisture-retaining layer, said overlap being bent over the edge surfaces of the perforations in the layer so as partially to cover them.

7. In a self-contained tobacco-moistener adapted for use as an integral unit, the combination with an apertured moisture-retaining layer of flexible moisture-impervious material secured to the sides of said layer so as to leave opposite edges of the latter exposed and adapted to project beyond the exposed edges of said layer on at least one side thereof, the said moisture-impervious material having apertures adjacent to at least one surface of the moisture-retaining layer which correspond to, and are slightly smaller than, the apertures in the said layer, so that an overlap is formed around the contour of each aperture in the moisture-retaining layer, said overlap being bent over the edge surfaces of the perforations in the layer so as partially to cover them.

8. In a self-contained tobacco-moistener adapted for use as an integral unit, the combination with an apertured moisture-retaining layer of flexible metallic moisture-impervious material secured to the sides of said layer so as to leave opposite edges of the latter exposed and adapted to project beyond the exposed edges of said layer on at least one surface of the moisture-retaining layer which correspond to, and are slightly smaller than, the apertures in the said layer, so that an overlap is formed around the contour of each aperture in the moisture-retaining layer, said overlap being bent over the edge surfaces of the perforations in the layer so as partially to cover them.

In testimony whereof I have signed my name to this specification.

KARL GRÜNWALD.
